TWIN BUSHING PULLER

Michael Claps, Denver, Colo.

Application July 24, 1947, Serial No. 763,206

2 Claims. (Cl. 29—265)

1

This invention relates to bushing pullers and more particularly to one which is adapted for the pulling of two bushings or equivalent members by one operation.

One of the objects of my invention is to produce a simple, inexpensive and efficient bushing puller which is adapted to simultaneously pull two axially spaced bushings or equivalent members of different size.

Another object is to produce a double bushing puller which employs simple pulling fingers not requiring resilient expansible means or other expensive structure.

A further object is to produce a bushing puller of the type described in which is embodied independent pulling fingers that can be readily replaced at a low cost in the event of damage, thus saving the expense of a complete new puller.

A more specific object of the invention is to produce a low cost bushing puller for the simultaneous extracting of the two pilot bushings associated with fluid couplings employed in automobile transmission systems.

Other objects of my invention will become apparent from the following description taken in connection with the accompanying drawings showing, by way of example, a bushing puller embodying the invention.

In the drawings:

Figure 1 is a perspective view of the twin bushing puller;

Figure 2 is a side view of the bushing puller with parts in section and broken away in order to show details of construction;

Figure 3 is a view showing the bushing puller in operation; and

Figure 4 is a detailed side view of one of the pulling fingers.

Referring to the drawings in detail, the improved twin bushing puller which I have disclosed by way of example as embodying my invention comprises a stem 1 made of two sections 2 and 3. The two sections are shown as of the same diameter and section 3 is provided with a reduced threaded inner end 4 which is arranged to be screwed into a threaded bore 5 in the inner end of the section 2 to couple the sections together. The outer end of this latter section 2 is formed with threads 6 over a substantial portion of its length and cooperating with this threaded portion of the stem is an elongated nut 7 having a hexagonal surface so that a wrench or other tool can be readily attached thereto to turn the nut. If desired, the two sections 2 and 3 of the stem may be made as a single piece, but

5 with the two-section form shown the stem section 3 can be replaced by a similar section of smaller or larger cross section to thereby condition the tool for a more universal use as will be come apparent.

Arranged for positioning on the smooth part of the stem are two bushing pulling fingers 8 and 9 of like construction which are shown in detail in Figure 4. Each of these fingers on its inner surface is provided with a longitudinally extending groove 10, the surface of which is cylindric having a radius of curvature the same as the cylindrical surface of the stem. The outer surface of each finger has stepped cylindric surfaces 11 and 12, the former having a greater radius of curvature than the latter with both cylindric surfaces being concentric with the cylindric surface of the groove 10. The inner end of the larger cylindric surface 11 has a shoulder 13 and the outer end of the smaller cylindric surface 12 has a shoulder 14. These shoulders are employed to engage the end edges of the two bushings during the pulling thereof to be performed by the bushing puller. Adjacent the outer end of each finger having the larger cylindric surface there is provided a slot 15 which is slightly angular to a plane at right angles to the longitudinal axis of the finger as shown in various figures.

30 The two fingers 8 and 9 are both formed to be somewhat less than a semi-cylinder so that when they are placed together with their grooves 10 in opposed relation, the shoulders 13 and 14 can be passed through the bushings to be pulled and which have an internal radius of curvature substantially the same as the radius of curvature of the cylindric surfaces 11 and 12. With such an arrangement it is seen that after the shoulders are passed through the bushings and the fingers are moved apart the shoulders can become placed behind the rear edges of the bushings. The previously referred to stem 1 provides the means for spreading the two pulling fingers after they are in operative positions and for additionally functioning to maintain said fingers in their operative position, as can be readily seen from Figures 1, 2 and 3.

40 The stem 1 is also employed for pulling the fingers in an axial direction so that the bushings can be removed and this is accomplished by means of a pin 16 extending transversely through the stem and extending from opposite sides of the stem so that it can be received in the slots 15 of the pulling fingers. In order that 45 the fingers can be maintained on the stem when

so desired, there is provided a cup-shaped sleeve 17 slidably carried on the stem. This sleeve can be slid to a position where the cylindrical portion thereof can be in surrounding relation to the ends of the fingers having the larger cylindric surfaces. The stem 1 also has slidability thereon, inwardly of the nut 7 and between the said nut and the sleeve 17, a bearing member 18 which is U-shape in form, the legs or extensions 19 thereof extending towards the fingers.

Referring specifically to Figure 3 which illustrates the tool being used in pulling two bushings simultaneously, there is shown a housing structure 20 in section. This housing structure is provided with a large bore 21 and a smaller bore 22 in axial alignment with and at the rear of the larger bore. Positioned in the inner ends of these two bores on suitable seats are bushings 23 and 24 which are employed to journal a shaft in the housing structure. A particular example of a housing structure in which bushings similar to the bushings 23 and 24 are employed is found in automobile transmissions employing fluid couplings as a unit thereof, the housing structure 20 being a part of the fluid coupling and the bushings 23 and 24 being mounted therein so as to journal the stepped end of a clutch shaft which transmits power to a change speed transmission and a propeller shaft connected to the wheels of a vehicle in a well known manner.

To pull the bushings 23 and 24 when such become worn so they can be replaced by new bushings, the two fingers of the illustrated improved twin bushing puller are first placed together with their grooves 10 in opposed relation. The fingers in this relation are then inserted through the open end of the outer larger bore 21 in the housing structure after the shaft has been removed. The insertion is made to a point where the shoulders 13 are slightly beyond the inner ends of the bushing 23 and the shoulders 14 are slightly beyond the inner end of the bushing 24. The fingers are now spread apart and the stem 1 is inserted between the two fingers and through the grooves 10 so as to further spread the inner ends of the two fingers apart and maintain the various shoulders behind the bushings with which they are to cooperate. The stem is so inserted that the ends of the pin 16 will pass into the spaces between the fingers. When the stem is inserted sufficiently that the ends of the pin are opposite the open ends of the slots 15 in the fingers, the stem is turned so as to place the ends of the pin 16 in the slots and thus connect the fingers to the stem. The sleeve 17 is then next slid over the ends of the finger having the larger cylindric surface. The puller is now in condition for pulling the bushings and to accomplish this all that needs to be done is screw up the nut 7. The nut will abut the base portion of the bearing member 18 and the ends of the extensions 19 will be brought into bearing engagement with the housing structure 20. By applying a wrench to the nut 7 and continuing to turn it, it will be seen that the stem 1 will be moved outwardly from the two bores in the housing. Since the fingers are connected to the stem by the bayonet joint connection comprising the pin and slots, the fingers also will be moved with the stem and consequently the shoulders 13 and 14 of each finger will engage behind the bushings and pull them outwardly from their bores.

In designing the tool, the extensions 19 on the bearing member should be of such length that the bushings can be pulled off their seats in the 75

bore. Also, each finger should be preferably designed so that the shoulders 14 thereof will engage the inner bushing 24 slightly prior to the outer bushing 23 during the pulling operation. With such an arrangement, it will only be necessary to start one bushing off its seat at a time and consequently less force will be necessary to be applied to the stem by the nut 7.

From the foregoing description of the details of my twin bushing puller and the operation thereof, it is seen that a minimum number of parts is employed to accomplish the simultaneous pulling of two bushings of different size. No springs are embodied in the bushing puller and the pulling fingers are designed to be independent members readily insertable in the bores having the bushing mounted therein. The fingers are easily connectable to the pulling stem. If damage should occur to either of the pulling fingers, a new pulling finger can be purchased at a small cost to repair the tool. It will not be necessary to purchase a complete new tool. Also, by constructing the stem in two parts, part 3 can be removed at any time and be replaced by another part similar to 3 but having a slightly smaller or greater diameter at the outer end thereof. When such is done, the tool can be adapted for use in pulling various sizes of inner bushings 24. In other words, the extent to which the shoulders 14 can be expended can be varied by merely employing several stem parts 3 of different cross-section for attachment to the part 2 of the stem.

Being aware of the possibility of modification in the particular bushing puller shown by way of example without departing from the fundamental principles of the invention, it is not intended that the scope of the invention be limited in any manner except in accordance with the appended claims.

What is claimed is:

1. In a bushing puller for simultaneously pulling two axially spaced bushings of different diameters or equivalent elements positioned in a housing structure, like independent pulling fingers each of which is made as a single integral piece and provided with longitudinally spaced shoulders for engaging the inner ends of the bushing to be pulled and also being so constructed that the shoulder means can be passed through the bushing with which said means is to engage, a stem of uniform diameter positionable between the fingers to maintain by direct engagement with the fingers the shoulder means thereof in engagement with the bushings, bayonet joint means for detachably connecting the fingers to the stem by a rotation of the stem only after said stem is positioned between the fingers, and means including screw means cooperating with the stem for moving the fingers and stem outwardly of the structure to thereby simultaneously remove the bushings.

2. A pulling finger for use with a bushing puller rod having a radially extending pin, said finger comprising an elongated member provided with a groove having a cylindric surface for receiving the rod and two outer cylindric surfaces of different radii of curvature, said outer surface also being provided with a bushing engaging shoulder adjacent the inner end of the larger cylindric surface and a bushing engaging shoulder adjacent the outer end of the smaller cylindric surface and said member having a slot for receiving the puller rod pin to detachably connect it thereto.

MICHAEL CLAPS.
